UNITED STATES PATENT OFFICE

ISIDOR ROTH, OF CHICAGO, ILLINOIS, ASSIGNOR TO NATURES RIVAL CO., OF CHICAGO, ILLINOIS, A CORPORATION OF ILLINOIS

FOUNDATION GARMENT

Application filed June 13, 1930. Serial No. 460,803.

The invention relates to improvements in foundation garments for women's wear and has for its primary object the provision of an improved construction of this character capable of economical manufacture and highly efficient in use.

Another object of the invention is the provision of a garment of the character indicated having a relatively heavy lower construction and a relatively light upper construction.

Another object of the invention is the provision of a garment of the character indicated especially adapted to serve as a combination of corset and brassière.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front perspective view of a garment embodying the invention;

Fig. 2 a partial transverse section of the same taken substantially on line 2—2 of Fig. 1;

Fig. 3 a partial vertical section taken substantially on line 3—3 of Fig. 1;

Fig. 4 a partial enlarged section taken substantially on line 4—4 of Fig. 1; and

Fig. 5 a partial section taken substantially on line 5—5 of Fig. 1.

The embodiment of the invention illustrated in the drawings comprises a lower portion 10 made of relatively heavy material such as satin and having suitable elastic gores or inserts 11 and 12 incorporated therein. The body thus formed is provided with depending supporter straps 13 as indicated. At the top of the front of the body two upward extensions 13 are formed as shown from the heavy material of said body and adapted and arranged to cover the bosoms of the wearer, a deep central recess 14 being formed between the extensions 13 as shown. At one side a suitable opening is provided and hooks and eyes 15 are arranged at the

edges thereof to serve as a means for adjusting the garment to the body of the wearer.

The upper portion 16 of the garment is formed of relatively lighter and more elastic material, such as rayon silk, such upper portion extending also downwardly into the gap 14 as shown. Suitable shoulder straps are also attached to the upper portion 16 to hold the same in proper position on the wearer.

Extending across the lower portion of each extension 13 is a reinforcement 18 in the form of a tuck formed in the material of each extension 13 to constitute a bosom support. Inwardly and downwardly inclined darts 19 are also formed in the upper portion 16 to cause a fullness above and adjacent each extension 13 to constitute a suitable brassière.

By this arrangement a suitable foundation garment is provided which is adapted and arranged to serve as a suitable combination corset and brassière having proper bust support. The specific form and arrangement of parts is a simple and efficient one for the purpose.

While I have illustrated and described the preferred form of construction for carrying my invention into effect, this is capable of variation and modification without departing from the spirit of the invention. I therefore do not wish to be limited to the precise details set forth, but desire to avail myself of such variations and modifications as fall within the scope of the appended claims.

Having thus fully described my invention, what I claim as new and desire to secure by Letters Patent is:

1. A garment of the class described comprising a foundation garment body of substantially tubular form adapted to surround and support the body of the wearer; shoulder straps for supporting said foundation garment on the wearer; right and left front reinforcing portions of heavy material connected to each other midway their adjoining front vertical sides and constituting the main front portion of the garment, the tops and bottoms of said reinforcing portions being separated from each other, the tops being extended upwardly to form bosom supports; an upper lighter garment portion extending

above, around and between said bosom supports and to which said shoulder straps are attached; and an elastic gore between the lower ends of said front reinforcing portions.

- 5 2. A garment of the class described comprising a foundation garment body of substantially tubular form adapted to surround and support the body of the wearer; shoulder straps for supporting said foundation garment on the wearer; right and left front reinforcing portions of heavy material connected to each other midway their adjoining front vertical sides and constituting the main front portion of the garment, the tops and bottoms of said reinforcing portions being separated from each other, the tops being extended upwardly to form bosom supports, transverse tucks being formed in said bosom supports; an upper lighter garment portion 20 extending above, around and between said bosom supports and to which said shoulder straps are attached, inwardly and downwardly inclined darts being formed in said upper portion above and outside of each bosom support; and an elastic gore between the lower ends of said front reinforcing portions.

In witness whereof, I have hereunto set my hand this 6th day of June, 1930.

30 ISIDOR ROTH.
